LOOSE LEAF BINDER

Filed April 10, 1931

INVENTOR

— Adolph G. Lotter —

BY Sir Walter Jones

ATTORNEY

UNITED STATES PATENT OFFICE

ADOLPH G. LOTTER, OF MILWAUKEE, WISCONSIN, ASSIGNOR TO STATIONERS LOOSE LEAF CO., OF MILWAUKEE, WISCONSIN, A CORPORATION OF WISCONSIN

LOOSE LEAF BINDER

Application filed April 10, 1931. Serial No. 529,074.

This invention relates to certain new and useful improvements in loose leaf binders of the type illustrated in Patent No. 1,804,626, May 12, 1931.

- 5 5 One of the objects of this invention is to provide a loose leaf binder having a simple and effective connection between the free ends of its extensible posts and the upper binder head, which holds the posts against 10 movement in either direction with respect to the upper binder head to insure the said binder head being carried upwardly away from the body of leaves during extension of the posts.
- 15 15 Another object of this invention resides in the provision of a connection of the character described between the free ends of the posts and the upper binder head which is readily releasable to permit the post ends to 20 be projected upwardly above the binder head to facilitate the application of extension sections.

And a further object of this invention is to provide a connection between the free ends 25 of the extensible posts and the binder head in which a slide bar carried by the head engages the posts to hold the same against movement in either direction with respect to the head and in which the stress incidental 30 to the application of tension to the posts is transmitted directly from the posts to the binder head to relieve the slide bar of any carrying strain.

With the above and other objects in view 35 which will appear as the description proceeds, my invention resides in the novel construction, combination and arrangement of parts substantially as hereinafter described and more particularly defined by the appended claims, it being understood that such 40 changes in the precise embodiment of the hereindisclosed invention may be made as come within the scope of the claims.

In the accompanying drawing, I have illustrated one complete example of the physical

embodiment of my invention constructed according to the best mode I have so far devised for the practical application of the principles thereof, and in which:

Figure 1 is a side view partly in elevation and partly in section of the binder heads of a loose leaf binder embodying my invention; 50

Figure 2 is a view partly in elevation and partly in section taken through Figure 1 on the plane of the line 2—2; 55

Figure 3 is an enlarged transverse sectional view taken through the upper binder head on the plane of the line 3—3 in Figure 1 showing the terminal member in elevation.

Referring now more particularly to the accompanying drawing, in which like numerals designate like parts throughout the several views, 5 and 6 represent the upper and lower binder heads, respectively, of a loose leaf binder between which a body of 60 leaves 7 is adapted to be clamped and protected by cover members not shown, hingedly connected with the binder heads by hinge pins 8 and 9. The binder heads are of tubular construction, preferably formed from 65 sheet metal or tubing of approximately rectangular shape in transverse section, and have their ends closed by caps 10 which provide means for mounting the hinge pins 8 and 9. 75

The binder heads are adapted to be connected by a pair of extensible flexible post members 11 having their lower ends passed through openings 12 into the lower binder head to be connected, as at 13, with nut members 14 slidable within the lower binder head. The nut members 14 have bores internally threaded with right and left threads to receive the corresponding threads of a screw 15 rotatably mounted in the lower binder. 80 The screw 15, upon being turned by a crank 16 or the like, effects longitudinal movement of the nut members 14 toward and away 85 from each other to retract and extend the flexible posts, as will be readily apparent. 90

The outer free ends of the flexible posts have socketed sections 17 secured thereto to receive the threaded studs 18 of terminal members 19. If desired, extension sections, 5 not shown, may be inserted between the socketed members 17 and the terminal members 19 to increase the length of the flexible posts.

The terminal members 19 extend through 10 openings 20 and 21 in the bottom and top walls respectively of the upper binder head, and the top wall has its portions surrounding the openings 21 depressed to form pockets 22 to receive enlarged heads 23 on the extreme outer ends of the members 19. These 15 enlarged heads 23 prevent downward movement of the post sections through the upper binder head upon the application of tension to the flexible posts. The strain incidental 20 to the application of tension to the posts is thus imparted directly to the top wall of the upper binder head.

As it is desirable to have the upper binder head move away from the body of leaves 25 during extension of the posts a releasable connection between the binder head and the posts is provided. This connection is effected by a slide bar 24 mounted within the upper binder head and provided with key 30 hole openings 25, the large portions 26 of which are of a size to permit the posts to be passed therethrough and the smaller portions 27 being engageable with the reduced annular or neck portions 28 formed in the 35 medial portions of the terminal members. With the slide bar moved to its position engaging its key hole slots with the neck portions in the terminal members, it is apparent that any downward pull or tension on the 40 part of the flexible posts is transmitted directly to the upper binder head.

The slide bar 24 is maintained in proper spaced relation with respect to the top and bottom walls of the binder head by foot members 29 projected from its bottom and by the bottom edges of the depressed pockets 22 in the top wall of the binder head, and if desired a spring 30 may be employed to take up any slack and hold the bar in its lowermost position.

From the foregoing description taken in connection with the accompanying drawing, it will be readily apparent to those skilled in the art to which an invention of the character 55 described apparatus, that the connection afforded by the slide bar engaging the grooves in the terminal members at the free ends of the flexible posts is readily releasable to permit the posts to be projected through and 60 above the upper binder head if desired, and that the slide bar does not carry any of the clamping stress, effected by applying tension to the posts.

I claim:

65 1. In a loose leaf binder having a pair of

binder heads, and substantially flexible post members extensibly connected with one head and each such post member being passed entirely through aligned openings in the other head, means on the extreme ends of said post members adapted to engage said other head to prevent the post members being pulled through the openings in said other head upon retraction thereof, and a member slidably mounted within said other head having means thereon engageable with the post members to prevent movement of the post members through said opening in the other direction and means to move said slidably mounted member to release said last named means whereby said post is free to move in said last named direction. 70 75 80

2. In a loose leaf binder having a pair of binder heads between which loose leaves are to be clamped and substantially flexible post members extensibly connected with one binder head, each post member being adapted to have its free end passed entirely through openings in the other binder head, terminal members on the free ends of said post members passing through said openings and having enlarged outer extremities to prevent movement of the terminal members through the openings in one direction, a member slidably mounted within said other binder head, and abutments on said terminal members engageable with said last named member to prevent movement of the post members through the openings in the other direction. 90 95 100

3. In a loose leaf binder having a pair of binder heads adapted to clamp a plurality of loose leaves, substantially flexible post members extensibly connected with one head adapted to have their free end portions passed entirely through openings in the other binder head, terminal members on said free ends of the flexible post members passing through said openings and having reduced neck portions intermediate their ends, a slide bar within said other binder head and having key hole slots releasably engageable with said reduced neck portions of the terminal members to secure the binder heads against movement with respect to the post members, and enlarged heads on the terminal members adapted to engage said other binder head to transmit strain incidental to the application of tension to the posts directly to the said binder head and prevent the terminal members from being pulled through the openings in said binder head in one direction. 110 115 120

4. In a binder of the character described including a pair of binder heads and posts therebetween, one of said binder heads having a wall thereof adapted to contact the sheets of said binder and a parallel wall in spaced relation thereto, said walls being provided with aligned openings to receive the ends of the binder posts therethrough, a portion of said last named wall cooperating with 125 130

- means on one end of each of said binder posts to prevent withdrawal of said ends of said posts through said binder head in one direction and means slidably mounted between 5 said walls to prevent the movement of the posts through said binder head in the opposite direction.
5. In a binder of the character described, including a pair of binder heads and posts 10 therebetween, one of said binder heads having a wall thereof adapted to contact the sheets of said binder and a parallel wall in spaced relation thereto, said walls being provided with aligned openings to receive the 15 ends of the binder posts therethrough, a portion of said last named wall cooperating with means on one end of each of said binder posts to prevent withdrawal of said ends of said posts through said binder head, and a plate 20 slidably mounted between the walls of said binder head and releasably engaging portions of said posts to prevent movement of said posts through said head. 80
6. In a binder of the character described 25 including a pair of binder heads having binder posts therebetween, one of said binder heads having spaced parallel walls through which said posts pass, means to prevent the withdrawal of said binder posts from said 30 last named head in one direction, means slidably mounted between said walls to prevent the withdrawal of the binder posts from said head in the other direction and means resiliently urging said last named means 35 away from said first named means. 90
7. In a binder of the character described including a pair of binder heads, one of said binder heads having spaced parallel walls, a binder post passing through said walls a 40 plate mounted between said walls and having foot members attached thereto, said plate being adapted to releasably engage the binder post, and spring means constantly urging said foot members into engagement with 45 one of said walls. 105
8. In a binder of the character described including a pair of binder heads, and a plurality of binder posts therebetween, one of said binder heads having spaced parallel 50 walls through which said posts pass, a plate member having a plurality of feet thereon engageable with one of said walls to maintain said plate in spaced relation to said wall, said plate member being adapted to 55 releasably engage all of said binder posts simultaneously, and spring means constantly urging said feet against the wall with which they are engageable. 110
9. In a binder of the character described 60 including a pair of binder heads, and a plurality of binder posts therebetween, one of said binder heads having spaced parallel walls through which said posts pass, a plate member having a plurality of feet thereon 65 engageable with one of said walls to main- 115
- tain said plate in spaced relation to said wall, said plate member being adapted to releasably engage all of said binder posts simultaneously, spring means constantly urging said feet against the wall with which 70 they are engageable, and means on one end of said plate to move said plate in the plane thereof to engage or disengage the posts. 120
- In testimony whereof, I hereunto affix my signature. 75
